(57) CLAIM

The ornamental design for a slapping device, as shown and described.

DESCRIPTION

FIG. 1 is a front, top, right side perspective view of a slapping device showing the new design;

FIG. 2 is a right-side view thereof;

FIG. 3 is a left-side view thereof;

FIG. 4 is a bottom view thereof;

FIG. 5 is a top view thereof;

FIG. 6 is a front view thereof; and,

FIG. 7 is a rear view thereof.

The equal-length broken lines in the drawings depict portions of the slapping device that form no part of the claimed design.

1 Claim, 4 Drawing Sheets
